Primary Examiner — Rashida Johnson(74) Attorney, Agent, or Firm — Fross Zelnick Lehrman & Zissu, P.C.; Charles T. J. Weigell, Esq.(57) CLAIM

The ornamental design for garment, as shown and described.

DESCRIPTION

FIG. 1 is a front view of a garment showing my new design; FIG. 2 is a side view of the garment shown in FIG. 1 (with the other side view being a mirror image thereof); and, FIG. 3 is another side view of the garment shown in FIG. 1, shown with the arm removed.

The broken lines throughout the views represent the portions of the garment which form no part of the claimed design.
